BUILDING CORNER UNIT

Robert S. Maclean, Michigan City, Ind., assignor
to Mastic Asphalt Corporation, a corporation
of Indiana

Application April 24, 1936, Serial No. 76,212

4 Claims. (Cl. 20—5)

My invention relates to building covering materials and the like, and more particularly to corner units adapted to be utilized in connection with rigid or flexible building covering units of the type now in common use.

My invention relates specifically to a rigid corner unit capable of attachment to the structure of a building and may have portions which extend from the corner parallel to the meeting walls to cover the edges of the siding units.

One of the objects of my invention is to provide a corner unit that will be weatherproof and fire-resisting, as well as being exceptionally attractive due to the many designs and configurations which may be impressed thereon without detracting in any manner from the wearing qualities thereof.

Another object of my invention is to provide an improved corner unit of the type described that may be cheaply manufactured, be rugged in construction and be capable of long use and abuse without deteriorating from the appearance thereof.

A further object is to provide a rigid corner unit of the type described that will give the appearance of outset corner units upon the building.

A further object is to provide a corner unit of the type described that will have the appearance of brick corner construction and be capable of use in aligning and applying siding units.

A further object is to provide a corner unit capable of attachment to the building structure by concealed fastening means.

A further object of my invention is to provide a new process of manufacturing corner units of the type described, wherein by the steps taken the unit is reinforced so that it will withstand hard abuse and be more rigid when applied than the ordinary flat siding units.

A further object is to provide a process easily and simply carried out by ordinary unskilled workmen.

Other objects and advantages will be more apparent from the following description wherein reference is had to the accompanying two sheets of drawings, upon which

Fig. 1 is a perspective view of a sheet of insulating board showing a reinforcement that is laid upon the face thereof during one step of my improved process;

Fig. 2 is a similar view of the same board after it has been treated with a coating of asphalt and grits;

Fig. 3 is a similar perspective view of the

board turned upside down showing another step in the process of forming the corner unit;

Fig. 4 is a fragmentary cross sectional view taken on the line 4—4 of Fig. 3;

Fig. 5 is a perspective view showing a further step in the process of forming the corner unit;

Fig. 6 is a front perspective view of the complete corner unit;

Fig. 7 is a vertical cross sectional view taken generally on the line 7—7 of Fig. 6; and

Fig. 8 is a side perspective view of a modified form of corner unit constructed by the same process.

The corner units which are manufactured by the process I am about to describe, are constructed of ordinary flat rectangular strips of insulating board such as are well known in the art. These boards are not ordinarily used as exterior building covering for the reason that they are not water-proof or weather-proof. However, by a process which is described in the co-pending application of Robert S. Maclean and Charles W. Pollard, Serial No. 753,472, filed Nov. 17, 1934, such insulating boards are submitted to a process whereby a surface thereof is treated with asphalt and grits so that when a plurality of the covering units are placed upon the side of a building, a water-proof and weather-proof siding is provided.

Accordingly, in constructing the corner units which I provide, I utilize a rectangular sheet 10 of insulating board such as previously described, which is provided in suitable sizes and also provided with a pair of ship-lap edges 12 and 14 for a purpose which will be hereinafter explained. The first step in constructing my improved building units is to apply with a brush or other means a quantity of hot asphalt over a definite area 16 and then immediately place a layer of fine strips of a reinforcing fiber, preferably the sisal strips 18 indicated, upon the hot asphalt, so that the same will be adhered to the face 20 of the insulating board 10. The unit 10 is then placed upon the machine shown and described in the co-pending application mentioned, and treated to receive a layer of hot asphalt 22 and a layer of grits 24 upon the face 20 thereof.

In the illustration shown in Fig. 2 I have also shown a plurality of longitudinal mortar lines 26 and of transverse mortar lines 28, so that the board when covered resembles a section of a brick wall. It will be noted that the weather-proofing has been applied over the sisal strips 18 so that in addition to being secured to the

board originally by the thin layer of asphalt, they are now completely covered by the asphalt and grits which form the weather-proof surface of the unit.

5 The next step in my improved process is to turn the unit over on its face and with a suitable V-shaped router or other means, cut a cross groove 30 in the back side 29 of the board medially between the edges of the first treated portion 16. The groove 30 may be cut to a depth adjacent the exterior edge of the original board 10 and be smoothed out and finished with an emery wheel if desired.

10 After this has been done, the unit 10 is ready to be bent to the right angle shape shown in Fig. 5, forming a corner portion having the long extension 32 and the shorter extension 34. When the board has been turned as described, a quantity of hot asphalt is applied to the shaded 15 area 36 on the back side 29 of the unit and a reinforcing member 38 is applied thereto, being adhered by the asphalt or other means which has adhesive qualities. The reinforcing 38 is 20 preferably saturated felt or paper, although it will be understood that cloth, metal, wire mesh or any other suitable reinforcing medium may be 25 employed.

20 After the corner unit has been formed as shown in Fig. 5, due to the bending to complete the previously described operation, there will be more or less of a cracking of the cooled asphalt on the exterior face along the vertical bend line 40. It is next necessary to apply heat, for example with a blow torch, along this entire edge, melt the 25 asphalt to a certain degree and then apply a quantity of grits along this edge, rolling the same into the asphalt as it is melted and thereby completely sealing up and welding any and all cracks which may have formed during the bending process. It is also necessary at this time to apply a heated tool such as a bar to the longitudinal mortar lines 26 to secure at the corner the same identical depression or groove that is formed throughout the length of the units.

45 By the process I have explained, it will be obvious that an extremely rigid corner unit has been provided, one that is actually strengthened by this process to the extent that rough handling or long use will not have any effect upon the appearance of the same nor upon the rigidity with which it holds its position. Due to the steps of the process whereby after the bend has been made, the asphalt at the bend which as been subjected to a strain is again reheated and re-worked and new grits applied, it will be obvious that this step will materially aid in the preserving of the rigidity and in giving the appearance of a unit formed in its inception as a bent member.

60 In actual use the units are applied in connection with the siding units previously mentioned with the ship-lap edges matching with those of the adjacent units, enabling each unit to be nailed in position on the building before the

next adjacent unit is placed over the ship-lap edges.

5 In Fig. 8 I have illustrated a modified form of corner unit 50 constructed in the manner that I have described but which in addition to the steps described is coated upon its exposed edges 52 and 54 with a coating of asphalt and grits so that the same can be applied over either flexible 10 building covering units or rigid building covering units that are applied without any attempt to fit in with a unit such as shown in Fig. 6. The unit 50 is provided with the lower ship-lap edges 56 and the upper ship-lap edges 60 so that the same can be applied to a building and overlap adjacent lower units. This type of building corner unit has been found to be very attractive in that it gives an offset corner edge and has been found very practical in that as previously mentioned, it is not necessary to attempt to match up the siding units with the corner unit as is necessary using the units shown in Fig. 6.

15 While I have illustrated and described a specific embodiment of my invention and the preferred process of manufacturing the same, it will be obvious to those skilled in the art that changes and modifications may be made both as to the specific details in the corner unit and in the particular process which has been described. I do not wish to be limited in any material way to the exact 20 details shown; rather what I desire to secure and protect by Letters Patent of the United States is:

I claim:

1. A corner unit capable of attachment to building corners to provide a weather-proof and decorative covering therefore, said unit constructed of a flat rigid composition board treated upon one surface with a continuous layer of asphalt and grits, grooved upon a back surface and bent to the desired angle and reinforced both upon its back side and upon its front side under 35 said layer and adjacent the bend.

2. A rigid corner unit of the type described constructed of a flat composition board, said board having a fiber reinforcement placed over an area upon its outer side, asphalt and grits 45 covering said outer side and reinforcement, said board cut for the major portion of its thickness upon its back side and bent to a desired angle and a reinforcing member applied to said corner upon the inside of said board.

3. A rigid corner unit of the type described constructed of a rigid bent composition board covered upon its outer surface with a continuous layer of weather resistant material and a flexible 50 reinforcing member underlying said material at 55 said bend.

4. A rigid corner unit of the type described constructed from a rigid bent composition board, weather-proof material, coating the exterior surface of said board, reinforcing means adhering to the inside and outside of said board at said bend, said material covering said outer reinforcing means.

ROBERT S. MACLEAN.
